Patented July 25, 1916

Archiebald A. Breast ^{Inventor}
Frank E. Kogel ^{Attorney}

UNITED STATES PATENT OFFICE.

ARCHIBALD A. BREAST, OF COLUMBUS, MISSISSIPPI.

TRACE-CARRIER.

1,192,742.

Specification of Letters Patent. Patented July 25, 1916.

Application filed November 9, 1915. Serial No. 60,557.

To all whom it may concern:

Be it known that I, ARCHIBALD A. BREAST, a citizen of the United States, residing at Columbus, in the county of Lowndes and State of Mississippi, have invented certain new and useful Improvements in Trace-Carriers, of which the following is a specification.

My invention relates to an improvement 10 in a trace carrier.

It consists in a wide and narrow band, the latter superimposed on the former and permanently stitched thereto at intervals, with an unstitched portion between the stitching 15 and a buckle of less width than the wide band, having slots therein to receive and by means of which the buckle is slidably connected with the narrower band with a portion of the metal forming the buckle 20 between the slots raised and bent to form a hook and upturned guards adjacent thereto where the trace rests and adapted to prevent the chain forming the trace from becoming detached from the hook.

25 In the accompanying drawings: Figure 1 is a view in side elevation; Fig. 2 is a sectional view; Fig. 3 is an edge elevation of the buckle; and Fig. 4 is a detached view in perspective of the buckle.

30 The numerals 1 and 2 represent a wide and narrow band or layer respectively, the narrower band or layer 2 being superimposed upon the wider band or layer 1, and having portions 3 and 4 stitched thereto.

35 The numeral 5 indicates a buckle. This is preferably stamped from a sheet metal plate of rectangular form having two parallel transverse slots 6, 6, and 7, 7, at the upper and lower ends through which the narrower band 2 passes out and in alternately as shown, in Fig. 3 and which admits of the buckle being adjusted up and down and held where placed by frictional engagement. While the length of these slots 6, 6 and 7, 7 45 approximately correspond to the width of the narrower band 2, the entire width of the buckle is considerably less than the wider band 1, so that the edges of the buckle are prevented from chafing and cutting into the 50 skin of the draft animal.

The entire center of the buckle is raised and more or less rounded and slotted as at 8, and bent and fashioned to form an upturned and inturned hook 9 to which the trace 10 is hooked and the guard flanges 11, 11, are disposed diagonally, and at each side of the hook, so that the inner end of the hook extends within the plane of the outer edges of the guard flanges, thereby forming a substantial closure of the hook against the band 2 when 60 in position, and in that way along with the protection of the guard-flanges preventing the accidental detachment of the trace. The raised and curved base formation of the hook gives added strength and support 65 thereto.

From the foregoing it will be seen that a strong and easily adjustable buckle is provided which will preclude accidental detachment of the trace, which cannot chafe or 70 irritate the draft animal by pressing upon or cutting into his skin.

I claim:

1. A trace carrier comprising two bands of different widths, the narrower of which is 75 superimposed and secured at intervals to the wider band, and a buckle wider than the narrow band and of less width than the wide band, slidably secured upon the narrower band and held thereupon frictionally, said 80 buckle having an upwardly and inwardly turned hook between the points of frictional engagement with the narrower band and provided with diagonally disposed out-turned guards or flanges which extend into 85 a plane outside of that in which the free end of the hook terminates.

2. A back band buckle comprising a sheet-metal plate having a pair of transverse slots at each end and struck-up at the center, and 90 having an approximately U-shaped slot formed therein, the edges of which are curved outwardly from one side of the buckle, and the center fashioned into an inwardly-turned tongue, which intersects 95 the outermost plane of the edges and terminates approximately in the plane of the plate.

In testimony whereof I affix my signature.
ARCHIBALD A. BREAST.
